* cited by examiner

Primary Examiner—Robert M. Spear(74) *Attorney, Agent, or Firm*—Christensen O'Connor Johnson Kindness PLLC(57) **CLAIM**

The ornamental design for a display sign, as shown and described.

DESCRIPTION

FIG. 1 is a front view of a display sign of the present design; FIG. 2 is a side (edge) view of the display sign of FIG. 1; and,

FIG. 3 is a back view of the display sign of FIG. 1. The broken lines in the drawings represent environmental structure only and form no part of the claimed design.
